UNITED STATES PATENT OFFICE

92,653

DESIGN FOR AN INDICATOR

Aubrey Hart, New York, N. Y.

Application March 3, 1934, Serial No. 50,935

Term of patent 3½ years

To whom it may concern:

Be it known that I, AUBREY HART, a citizen of the United States, residing at New York, in the county of New York and State of New York, have invented a new, original, and ornamental Design for an Indicator, of which the following is a specification, reference being had to the accompanying drawing, forming part thereof.

I claim:

The ornamental design for an indicator substantially as shown.

AUBREY HART.
